UNITED STATES PATENT OFFICE.

MARSHALL B. LLOYD, OF MENOMINEE, MICHIGAN, ASSIGNOR, BY MESNE ASSIGNMENTS, TO LEVI H. GREENWOOD AND GEORGE A. KEYWORTH, BOTH OF GARDNER, MASSACHUSETTS, AND WILLIAM E. HOLMAN, OF LEOMINSTER, MASSACHUSETTS, TRUSTEES.

METHOD OF AND MEANS FOR BINDING THE EDGES OF REED FABRIC AND THE LIKE.

Application filed August 20, 1920. Serial No. 404,799.

To all whom it may concern:

Be it known that I, MARSHALL B. LLOYD, a citizen of the United States, and a resident of Menominee, county of Menominee, and State of Michigan, have invented certain new and useful Improvements in Methods of and Means for Binding the Edges of Reed Fabric and the like, of which the following is a specification.

- 10 My invention relates generally to the production of reed articles, but is concerned more directly with a method and means whereby a piece of reed fabric or the like may be properly prepared for use. When 15 I speak of reed fabric I refer to a fabric which is composed of spaced stakes over and under which filler strands are intertwined. Such fabric may be composed of the natural reed or the so-called fibre reed, or it 20 may be composed in part of each. In any event, it is of a fibrous character of such a nature as to be of naturally pleasing character and also such as is admirably adapted to receive color or tint applications. 25 The invention in some of its aspects also is applicable to other fibrous fabrics. Heretofore I developed the practice of weaving fabric and the like independent of the frame, or where the article had no 30 frame as a piece of fabric not necessarily in the form or shape desired in the finished article.
- In the practice of my inventions I find it 35 desirable to bind the edges of the fabric and the desired rigidity and stability is preferably secured by using some such material as metal. Such a metallic bound fabric is admirably adapted for use in the practice of my inventions before alluded to in so 40 far as it is functionally considered. Reed and similar articles, however, are to a large extent used because of their pleasing appearance and for the delightful color effects derivable therewith. The metallic 45 strip is for this reason objectionable in that it may not take the same kind of paint or coloring medium that is adapted or desired for use with reed fabric, or if it does take

a paint of this character the appearance thereof is so distinctly different as to make 50 it unduly noticeable.

It is an object of my invention to provide means for binding the edges of reed fabric and the like which shall functionally be adapted to this use and which shall blend 55 or coact in appearance favorably with the reed fabric.

Other objects of my invention are to provide binder means which can be produced rapidly at low cost; which can be quickly 60 and easily applied to the fabric, and which shall generally be better adapted for use with reed fabric and the like than binder means heretofore devised.

My invention consists generally in a 65 binder strip for reed fabric and the like; in a method of producing same; and in the steps, acts and stated sequence thereof whereby the above named objects, together with others that will appear hereinafter, are 70 attainable; and my invention will be more readily understood by reference to the accompanying drawings which illustrate what I consider at the present time to be the preferred embodiment thereof. 75

In said drawings:

Fig. 1 is a plan view of a piece of metallic strip material such as is used in part of the binder.

Fig. 2 is a plan view of a portion of strip material which in use is joined or united to the strip shown in Fig. 1. 80

Fig. 3 is a plan view showing the strip of Fig. 2 superimposed upon the strip of Fig. 1. 85

Fig. 4 is a sectional view, on an enlarged scale, substantially along the lines 4—4 of Fig. 3.

Fig. 5 is a plan view illustrating the next step in the formation of the binder strip. 90

Fig. 6 is a cross section substantially on the line 6—6 of Fig. 5, but on an enlarged scale.

Fig. 7 is a bottom view illustrating the next step in the formation of the binder 95 strip.

Fig. 8 is a sectional view thereof, on an enlarged scale, viewed along the line 8—8 of Fig. 7.

Fig. 9 is a fragmentary view of a piece 5 of reed fabric showing the edge binder applied thereto.

Fig. 10 is an enlarged sectional view on the line 10—10 of Fig. 9.

Fig. 11 is a view illustrating a modified 10 binder strip embodying my invention.

Fig. 12 is a view thereof along the line 12—12 of Fig. 11 but on an enlarged scale.

Fig. 13 is a plan view of a still further 15 modification of my invention.

Fig. 14 is a sectional view showing the element of Fig. 13 formed for application to the fabric; and

Fig. 15 is a perspective view of a reed article embodying my invention.

Referring now particularly to Figs. 1 to 20 inclusive, 1 represents a piece of metal of a character such that it may be bent and folded without cracking or breaking. 2, represents the strip of material which is 25 of a fibrous nature so that its characteristics shall approximate those of the reed fabric. Various materials may be suitable for this purpose among which may be noted cloth, paper, fibre sheeting and the like.

If paper is used I prefer to treat it as by 30 applying sizing or other material which shall make it resistant to moisture and other conditions to which it will be subjected in use. Preferably I make the strip 2 somewhat narrower than the strip 1 so that when 35 superposed thereon, as shown in Figs. 3 and 4, portions 3 and 4 of the metal strip project there beyond. I desire firmly to secure the strip 2 to the strip 1 and to this end fold

40 or form the strip portions 3 and 4 over the strip 2 as is well shown in Figs. 5 and 6. In this event the strip 2 is held in place on the metal strip 1.

More firmly to secure the strips 1 and 2 45 together and also to stretch the strip 2 tightly over the strip 1, I reversely bend the edge portions of the composite strip shown in Figs. 5 and 6 to the form shown in Figs. 7 and 8. At the same time by this operation 50 the entire upper surface as well as the edges of the metal strip are covered by the fibre strip and hence hidden from view.

The application of the binder strip to the 55 fabric will be well understood by reference to Figs. 9 and 10 wherein 5 represents the stakes of reed fabric and 6 the filler strands. As shown, the composite strip is secured to the fabric by folding the strip substantially 60 along the middle, meanwhile positioning the filler strands and strip in intimate relation. In this manner the strip is secured to the fabric and if desired more firmly to lock the fabric and binder together the strip may 65 be folded back from the dotted line position shown in Fig. 10 to the full line. This

binder strip serves to give rigidity to the fabric and still presents outwardly a surface which approximates that of the reed or reed fibre fabric resulting in the advantages before enumerated.

In Figs. 11 and 12 and I have shown a slightly different form of my invention wherein 7 is a metal strip preferably having marginal portions 8 folded back upon the body portion thereof. Around this element 75 I firmly secure, as by binding helically thereon, a strip of fibrous material 9 which may be of various materials but which preferably is made of paper. In this manner a composite binder strip is formed which is admirably adapted for use for the purpose intended.

In Figs. 13 and 14 I have shown still another modification of my invention and therein 10 is a strip of material and superposed thereon is a piece of adhesive tape 11. This composite strip may be bent to the U-form shown in Fig. 14 in which condition it can be easily applied to the reed fabric.

In Fig. 15 will be found a reed article in 90 which the edge binder strips are indicated at 12. These strips are of a form shown in Figs. 11 and 12, and it will be observed that they conform admirably with the wound frame members 13 of the article. The reed article 95 may be completely made up as shown in Fig. 15 and then the whole article tinted or colored as by spraying with an air brush and when completed the binder strips merge with and practically become a part of the fabric. In this manner, the desirable metallically reinforced edge is secured without the undesirable metallic prominence.

The many advantages of this invention will 100 be readily understood without further comment, but inasmuch as this disclosure will suggest to others modified constructions whereby the substantial objects and purposes of my invention may be attained I do 105 not wish to be limited to the specific steps or stated sequence thereof except only as may be necessary by the limitations in the hereunto appended claims.

I claim:

1. As an article of manufacture, a binder strip for fabric of the class described embodying therein a metallic strip having a fibrous covering, the edges of which are secured within folded relatively small edge portions of the metallic strip.

2. The method of making a binder strip of the class described that consists in providing a metallic strip, in providing a fibrous strip of less width than the metallic strip, superimposing the fibrous strip upon the metallic strip and folding relatively small marginal portions thereof over the fibrous strip.

3. The method of making a binder strip of the class described that consists in providing a metallic strip, in providing a fibrous

strip of less width than the metallic strip, superimposing the fibrous strip upon the metallic strip and folding marginal portions thereof over the fibrous strip, and then ¹⁵ reversely bending the fibre clamping portions of the metallic strip.

4. The method of making a binder strip of the class described that consists in providing a fibrous strip of less width than the ²⁰ metallic strip, superimposing the fibrous strip upon the metallic strip, folding marginal portions thereof over the fibrous strip,

and reversely folding the interlocked marginal portions of the metallic and fibrous strips.

15

5. As an article of manufacture, a binder strip for fabric of the class described embodying therein a metallic strip having a fibrous covering, the edges of which are secured within plait-like marginal portions of the ²⁰ metallic strip.

In testimony whereof, I have hereunto set my hand, this 26th day of July, 1920.

MARSHALL B. LLOYD.
